(57) **CLAIM**

The ornamental design for a wire caddy, thereof as shown and described.

DESCRIPTION

FIG. 1 is a perspective view.

FIG. 2 is a front view.

FIG. 3 is a rear view.

FIG. 4 is a left side view.

FIG. 5 is a right side view.

FIG. 6 is a top view; and,

FIG. 7 is a bottom view.

The dotted line disclosure shown in the drawings is not claimed and forms no part of the claimed invention.
